UNITED STATES PATENT OFFICE

GEORGE P. LUCKEY, OF DAYTON, OHIO

SENSITIVE ALTIMETER

REISSUED

Application filed June 27, 1923. Serial No. 648,057.

This invention relates to altimeters and has particular reference to an altimeter of extreme sensitivity and range for aeronautical use.

5 It is the prime object of this invention to provide an altimeter that will be rugged, compact, accurate and sensitive to the smallest change in altitude and which will be accurate over a great range of variation in 10 altitude.

It is the further object to provide an instrument of this character, with a temperature compensating device which may be easily adjusted so as to simultaneously vary the 15 effective length of a lever arm in two series of transmitting systems connected to two separate aneroid capsules.

Further objects will be more fully set forth in the attached specification and claims.

20 In the drawing:

Fig. 1 is a sectional elevation of an embodiment of my invention.

Fig. 2 is a top plan view, and 3 is a detail of the link connections between the 25 aneroid capsules.

Referring to the drawings, Fig. 2 is a bowl-shaped housing having a glass or other transparent top 4 and carrying the operating mechanism including dials 6 and 8 with zero 30 adjusting mechanism 10 for the former. Within the bowl 2 and secured to the same is a skeleton supporting disk 12 upon which two bellows or aneroid capsules 14 preferably of metal, are mounted, while supported 35 from the disk 12 are yokes 16 and 18, upon which the levers, bearings and gear trains are mounted. To the inner ends of the capsules are rigidly secured in any suitable manner, projections 20, 22, pivoted to arcuate 40 links 24 and 26 in turn pivotally connected with angularly adjustable arms 28, 30 guided by auxiliary arms 34 and 32, which are pivoted together at 36 on a shaft 38. The shaft 38 is mounted in jewelled bearings and provides a support for a counterbalanced 45 segmental gear 40, positioning collars being provided therefor on the shaft. The segmental gear 40, meshes with a pinion 42, carried by a countershaft 44, which in turn carries a 50 gear 46, meshing with a pinion 48, carried by

a second countershaft 50. The countershafts 44 and 50, are also mounted in jewelled bearings and carry at their outer ends pointers 52 and 54 respectively, which are arranged to move over the faces of dials 8 and 6. The gear ratio between the gears 46 and 48 is properly chosen so that the desired number of revolutions of the hand 54 for one revolution of the hand 52 are obtained. The dials 6 and 8 are graduated in equal spaces, the first for example, being graduated for one thousand feet change in altitude per revolution, and the latter for any desired multiple of the one thousand feet change.

Referring more particularly to Fig. 3, the links and arms connecting the projections 20 and 22 to the shaft 38, are especially designed to change the motion of the aneroid capsules for equal changes in pressure, into a uniform circular motion by a proper proportion of the lengths of the various arms and links, the distance between the aneroid ends of these arms and the pivot 36, the lateral spacing of the links 24 and 26, and the distance between the point 36 and the inner ends of the links 24 and 26. The non-uniform rectilinear motion of the capsules is changed into a uniform circular motion by this mechanism and the scales therefore contain equal graduations. This is absolutely necessary in an instrument in which two pointers are used wherein one pointer travels over the same scale a number of revolutions. If a square scale or other irregular scale was used, it would be impossible or at least extremely confusing, to obtain the reading of the pointer.

The ends of the links 24 and 26 are attached to the point 36 through an adjustable linkage 28, 34. Calling the end of the link 24, *a*, the point 36, *b*, and the end of link 26, *c*, the distance *ab* is an imaginary link connecting 24 to 36, the length of which may be varied manually if desired, in order to adjust the range of movement of the pointer. This may be necessary in case different aneroid capsules are used from those intended, or in case one is replaced in a finished instrument. By this means also, it is possible to make the scales in quantities with the assurance that the instrument may be easily

adjusted to accommodate itself to this scale. The arms or links 28 and 30, are attached together and to an adjusting screw 56. By adjusting this screw 56, lever arms *ab* and *bc* 5 are simultaneously lengthened or shortened and to an equal degree. The distance between the line of action of projection 20 is substantially aligned with *a* in its normal position and the straight line *abc* as shown, is 10 normally, at zero reading of the instrument, at such an angle to the line of motion of the projections 20 and 22 that decreasing lineal increments of motion of the projections 20 and 22 inward will produce equal arcuate increments of motion of the points *a* and *c* about 15 axis 38. Since the total angular movement of the line *abc* is only about 30 degrees, the proper location of the line *abc* in relation to the line of motion of the projections 20 and 20 22 may be chosen so that the shaft 38 is rotated through substantially equal angles as 25 the pressure of the outside air varies equal amounts, and as the bellows 14 expands in decreasing amounts which vary, like a spring, about as the square root of the changes of 30 air pressure.

In order that compensation may be made for temperature changes, two links such as the links 28 and 30, or the links 32 and 34, 35 or the adjusting screw 56 of the toggle adjusting mechanism, may be made of the material or combination of materials of suitable coefficients of thermal expansion. With such a construction the arms *ab* and *bc* may 40 be automatically varied in a suitable manner by a temperature change of the atmosphere or of the instrument and which will correct errors introduced by the expansion of parts of the mechanism.

40 40. What I claims is:

1. In an instrument having sealed atmospheric pressure responsive means, a plurality of dials, an indicator for each of said dials, one of said dials and indicators being geared 45 to the other so as to move only a fraction of a revolution for each complete revolution of the other, link mechanism connecting said pressure responsive means to said indicators for transforming unequal movements of said 50 means into uniform rotary movement of said indicators, and a device included in said mechanism for changing the ratio of the movement of the said indicators in respect to the movement of said pressure responsive 55 means.

2. In an instrument having atmospheric pressure responsive means, a large and a small dial, a large and a small indicator adapted to register over said dials respectively, gearing interconnecting said indicators so 60 that said small indicator moves a fraction of a revolution for each complete revolution of the larger indicator, and a system of pivotally connected links connecting said indicators 65 to said pressure responsive means for trans-

forming unequal movements of said pressure responsive means into uniform rotary movements of said indicators.

3. In an altitude indicator in combination, a plurality of spaced atmospheric pressure responsive bellows, a dial, a pointer adapted to register over said dial, link means between each of said bellows and said pointer for transferring movements of said bellows to said pointer, and a unitary adjusting means for said link means to simultaneously and equally vary the ratio of the movement of each of said bellows to the movement of the pointer.

In testimony whereof I affix my signature. 80
GEORGE P. LUCKEY.
